(57) **CLAIM**

The ornamental design for a jar, as shown and described.

DESCRIPTION

FIG. 1 is a perspective view of a jar showing our new design;
FIG. 2 is a front elevational view thereof in an enlarged
scale, the rear, right and left side elevational views being
mirror images thereof;

FIG. 3 is a top view thereof in an enlarged scale; and,
FIG. 4 is a bottom view thereof in an enlarged scale.

The broken line showing of the environment is for illustrative
purposes only and forms no part of the claimed design.
